WALKING, SITTING, AND STANDING DOLL

Joseph Zanca, Brooklyn, N. Y.

Application July 21, 1955, Serial No. 523,452

8 Claims. (Cl. 46—149)

This invention relates to new and useful improvements in dolls.

More particularly, the present invention proposes the construction of an improved sitting, standing and walking doll which can be made easily and quickly to sit, stand or walk merely by handling the doll in a normal and natural manner.

As a further object, the present invention proposes forming the doll with a body having leg openings and with two legs connected together through the openings so that when one leg is moved in one direction the other leg will be moved to simulate a step.

Still further, the present invention proposes constructing the legs with annular hip bosses and providing inner and outer flange rings to fit on each side of the bosses with removable knock-out pins to hold the rings to the bosses.

Another object of the present invention proposes forming the doll with a pair of cam members mounted in the body between the legs for coaction with the pins extending through the flange rings and bosses.

A further object of the present invention proposes constructing the doll with a resilient member extending through the body between the legs and biasing the pins toward one another and against the cam members.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side view of a doll constructed and arranged in accordance with the present invention.

Fig. 2 is a sectional view taken on line 2—2 of Fig. 1.

Fig. 3 is a perspective view of the standard and lever shown in Figs. 1 and 2.

Fig. 4 is a perspective view of one of the cam members shown in Fig. 2.

Fig. 5 is a side view of one of the lever connecting rods shown in Figs. 2.

Fig. 6 is a side view of the inner side of one of the legs.

Fig. 7 is a sectional view taken on line 7—7 of Fig. 6.

Fig. 8 is a perspective view of one of the pins and cam members shown in Fig. 2.

Fig. 9 is a perspective view of a modified cam and lever connecting rod arrangement, showing these members to be integral.

Referring more particularly to the drawings, the sitting, standing and walking doll of the present invention is designated generally by the reference numeral 15.

Doll 15 has a head 16, a body 17, two arms 18 and 19, and two legs 20 and 21, the legs having feet 22 and 23 with socks 24 and shoes 25. Preferably the head, body, arms and legs are made of pliable material such as vinyl plastic.

Body 17 has a hollow lower portion 26 with opposed

leg openings 27 and 28 and legs 20 and 21 have annular upper hip bosses or boss portions 29 and 30 slightly smaller in outside diameter than the diameter of the leg openings 27 and 28 in the body.

Outer flange rings 31 and 32 are provided with ring portions 33 and 34 adapted to fit around the bosses or boss portions 29 and 30 and flanges 35 and 36 adapted to be disposed against the outer surfaces of the body at the leg openings 27 and 28. The ring portions 33 and 34 are adapted to fit inside the leg openings 27 and 28.

Inner flange rings 37 and 38 are provided to fit inside the bosses or boss portions 29 and 30 to hold the bosses or boss portions between the inner and outer flange rings. The flange rings 31 and 37 and boss or boss portion 29 have alignable pin openings 39, 40 and 41 for a knock-out pin 42 and flange rings 32 and 38 and boss 30 have like openings for a knock-out pin 46. In this manner the flange rings are secured to the bosses. Sleeves 47 and 48 are provided for the pins 42 and 46 inside the inner flange rings 37 and 38.

Tubular cam members 49 and 50 have cam portions 51 and 52 adapted to bear against the pins 42 and 46. The cam members 49 and 50 have axial bores 53 and 54, lever connecting rod receiving chambers 55 and 56 and lever connecting rod slot openings 57 and 58 to the chambers 55 and 56, respectively.

Lever connecting rods 59 and 60 have circular lower portions 61 and 62 adapted pivotally to fit in the chambers 55 and 56 of the cam members 49 and 50 and upper straight portions 63 and 64 adapted slidably to fit in and extend through the slot openings 57 and 58 of cam members 49 and 50.

A standard 65 has trunnion portions 66 and 67 and an axial bore 68. The standard has an arcuate shaped lower portion 69 adapted to fit in the body between the legs. Standard 65 also has an upper portion 70 with a lever 71 pivotally mounted on the top or upper portion 70. Lever 71 has free end portions 72 and 73 with openings 74 and 75 to receive the upper ends 76 and 77 of the lever connecting rods 59 and 60.

The lever connecting rod receiving chambers 55 and 56 of cam members 49 and 50 pivotally and slidably fit over the trunnion portions 66 and 67 of the standard 65.

A resilient member 78 having end hooks 79 and 80 fits through the axial bore 68 of the standard 65, through the axial openings of the tubular cam members 49 and 50, through the circular lower portions 61 and 62 of lever connecting rods 59 and 60, and partially through the inner flange rings 37 and 38 with the hooks 79 and 80 hooked over the pins 42 and 46 and the resilient member in stretched condition.

The resilient member 78 thus holds the legs on the doll and also presses the pins 42 and 46 against the cam surfaces 51 and 52 of the cam members 49 and 50.

The operation of the doll is simple. When one leg is moved in one direction, the lever 71 moves the cam member adjacent the other leg through the connecting rod connected thereto and the cam surface of that cam member bearing against the pin of that leg causes movement of that leg in step fashion. Likewise the process is reversed when the first leg is moved back. Movement of the legs can be accomplished merely by "walking" the doll, holding its hand or hands and pulling forward or backward while the feet are on a walking surface.

While I have illustrated and described the preferred embodiment of my invention, it is to be understood that I do not limit myself to the precise construction herein disclosed and that various changes and modifications may be made within the scope of the invention as defined in the appended claims.

Having thus described my invention, what I claim as new, and desire to secure by United Letters Patent is;

standard having trunnion portions and an axial bore, said lever connecting rod receiving chambers of the cam members pivotally and slidably fitting over said trunnion portions of the standard, said standard having an arcuate shaped lower portion adapted to fit in said body between the leg openings.

7. A sitting, standing and walking doll comprising a body having a hollow lower portion with opposed leg openings, a pair of legs having annular upper hip boss portions, outer flange rings adapted to fit around said boss portions of the legs and extend inside the leg openings of the body, inner flange rings adapted to fit inside said boss portions to hold the boss portions between the inner and outer flange rings, and means pivotally and removably to hold the outer flange rings in said leg openings of the body, said means being pins extending through the outer flange rings, boss portions and inner flange rings and a resilient member extending between and removably connected with said pins, a pair of cam members pivotally mounted in said inner rings with cam surfaces bearing against said pins, a standard between said cam members, a lever pivotally mounted at the top of the standard in the body with two free end portions, a pair of lever connecting rods each having one end con-

20

nected with a free end of the lever and another end rotatably mounted in one of the cam members between the cam member and the standard, said resilient member extending through the cam members and the standard, said body and legs being of vinyl plastic and said rings, pins, cam members, lever, standard and lever connecting rods being of metal.

8. A sitting, standing and walking doll comprising a plastic body having a hollow lower portion with opposed leg openings, a pair of plastic legs having plastic annular bosses, a pair of outer metal flange rings adapted to fit around the bosses, a pair of inner metal flange rings adapted to fit inside the annular bosses, said two pairs of flange rings having alignable pin openings between the inner and outer rings and said bosses having like openings, and a pair of pins extendible through the inner and outer flange ring openings and boss openings removably to secure the inner and outer flange rings to the bosses.
